UNITED STATES PATENT OFFICE.

JACOB HAISH, OF DE KALB, ILLINOIS.

CAR-COUPING.

SPECIFICATION forming part of Letters Patent No. 372,906, dated November 8, 1887.

Application filed August 2, 1887. Serial No. 245,935. (No model.)

To all whom it may concern:

Be it known that I, JACOB HAISH, a citizen of the United States, residing at De Kalb, in the county of De Kalb and State of Illinois, 5 have invented certain new and useful Improvements in Car-Couplings; and I do hereby declare the following to be a full, clear, and exact description of the invention, such as will enable others skilled in the art to which it applies 10 pertains to make and use the same, reference being had to the accompanying drawings, and to letters or figures of reference marked thereon, which form a part of this specification.

My invention has reference to certain improvements in car-couplings; and it consists, more particularly, in mechanism by means of which the cars can be coupled and uncoupled from either side, and the attachment of the coupling assured against any casual displacement by reason of the jarring of the cars or otherwise.

My invention is more particularly intended to be applied to freight-cars, as in the use of the latter more frequent coupling and uncoupling is requisite.

In the drawings, Figure 1 is a side elevation of my invention, showing the coupling on the adjacent ends of two contiguous cars, with the side of one coupling partially cut away to 30 more fully exhibit the interior. Fig. 2 is an end view of one of the couplings. Fig. 3 represents a plan view of my improved couplings; Fig. 4, a detail view of the lock mechanism; and Fig. 5, a detail view of the coupling-arm, 35 showing how it is mounted upon the shaft.

A is the buffer.

B is the draw-bar, attached by means of the usual spring or in any suitable way to the car.

In the buffer A is seated the mechanism for 40 attaching and detaching the car. Each end of each car is furnished with the coupling, and as the parts attached to one end of the car are the exact counterparts of similar parts attached to the other end, I do not deem it necessary to 45 show or describe more than the mechanism attached to one end and explain the mode of connection to the adjacent end of the contiguous car.

While, as above stated, the parts attached 50 to one end of the car are the counterparts of similar parts attached to the ends of all the

other cars, yet the interrelation of the couplings is such that they are operative only when used in pairs—that is to say, one end of a car furnished with my invention can be attached 55 to the adjacent end of another car by means of my improved mechanism only when such adjacent end is likewise furnished with the improvement.

In the outer end of the buffer A are formed 60 recesses D and D', located, respectively, near the sides of said buffer, and also a central recess, E, the latter having outwardly-divergent walls and a vertical pin-hole, E', and no further description of the central recess is necessary than to say that it is uniform with and intended to be in function the same as the seat of the ordinary link-and-pin coupling, and designed to be used only when the adjacent car 65 is susceptible of coupling alone with the old 70 link-and-pin coupling.

Recess E may be above or below shaft G, as desired.

The walls of the recesses D and D' are downwardly-extending jaws F, through which, near the lower end thereof, is loosely seated a transverse rock-shaft, G. On one end of the shaft 75 G is seated a removable head, H, fixed to said shaft by the short transverse bolt H'. The shaft G, with the head H removed therefrom, 80 is passed through the jaws F from the opposite end of the buffer A. On that portion of the shaft G which rests in the recess D' is formed the lateral feather G', and on the shaft G, inside the recess D', is seated the coupling-arm 85 J, having its shank provided with a recess, J', conformable to the feather G', so as to be carried with the rotation of said shaft G. The outer wall of the recess D' has also an angular recess, D'', admitting the passage of said feather 90 G'. The coupling-arm J is seated loosely on the shaft G, and, while prevented by said feather G' from rotating on said shaft, said arm is free to adjust itself laterally on said shaft, so as to be more readily inserted in the corresponding 95 recess, D, of the adjacent car and to enable said arm to adjust itself to any lateral movement, oscillation, or changed position of the adjoining ends of the cars.

On the outer wall of the recess D' is formed 100 the cam projection K, having a vertical rear wall, K'. A collar, M, is rigidly formed on

the shaft G, outside of said recess D', and the inner face of said collar M is provided with a recess, M', adapted to engage the cam K and lock the shaft G. The cam K and recess M' are so placed and related that they are in engagement when the coupling-arm J is in a horizontal position and resting upon the corresponding shaft G of the adjacent car. This provision prevents any casual lifting of said arm J in the movement of the train, and therefore serves to insure the permanency of the coupling. On the opposite end of the shaft G, and outside of the buffer A, is seated, in any suitable manner, a coiled spring, N, having an expansive action, and therefore serving to hold the cam K and recess M' in engagement.

The permanency of the coupling is still further assured by providing the end of the shaft G with a fixed transverse rod, G², perpendicular to the line of the arm J, and extended upward sufficiently to be seated in the recess C', formed in the edge of the platform C, and to be held therein by the expansive action of the 25 spring N.

In the adjacent coupling the recess D is opposite the recess D'. In the recesses D' are respectively seated the coupling-arms J, and when the coupling is completed the outer end 30 of each arm J rests upon the other shaft G in the opposite recess, D. The outer end of the arm J has a downward projection, J², substantially vertical, which passes down behind the shaft G in the recess D and is the point 35 where the draft is applied.

From my own observation and such information on the subject as I have been able to obtain my conviction is that the best results would be attained if there were little or no 40 slack in the coupling, and in that view I have shown the buffers A nearly contiguous when in use, but having their adjacent ends slightly convex laterally, so as to permit the necessary curvature of the train; but the horizontal

45 portion of the arm J may be made of any desired length, so as to produce a slack in cases where that is deemed advantageous. The shaft G can be operated from either side of the car. Should the operator be at that end

50 of the shaft G upon which the spring N is seated, he would disengage the bar G² from the recess C' and the collar M from the cam K by pushing the shaft G a sufficient distance inward, when the car would be uncoupled by

55 partially rotating the shaft G, and thereby carrying the arm J upward and back into the recess D'. This involves about a half-revolution of the shaft G and brings the opposite end of the cross-bar G² into the recess C', where 60 said bar is held by the action of the spring N, and also the arm J is not only held out of engagement, but the buffer A is in condition to permit the use of the ordinary link-coupling, if required. Should the operator be at the

65 opposite side of the car, he would uncouple the car by seizing the bar G² and drawing the

shaft G toward him sufficiently to release said bar and said collar M from the cam K and partially rotate the shaft G, as aforesaid.

The coupling of the car is effected in the same manner, except that the shaft G is rotated in the opposite direction. Across the upper surface of the buffer A is placed the platform C, which, when the cars are coupled, substantially fills the interval between the 75 cars, affords protection against any falling between the cars, and also serves as a cover or roof for the coupling mechanism, and prevents the latter from being encumbered with snow or ice. The platform C can be made folding or 80 removable, if so desired.

The parts can be constructed of any desired size and strength. The arm J, if preferred, can be furnished with more of a hook form at the end. The advantage of the present formation of the end of said arm is that the cars can be coupled or uncoupled when in actual contact without any relative movement.

The device for holding the arm J in engagement with the shaft G dispenses with any inward or hooked projection of the outer end of said arm, and thereby the cars can be coupled when in actual contact, as aforesaid, and when the draft is applied there is no slackening up of the train or opening between the buffers, as 95 occurs when the coupling device has the said hook-like formation. So, also, the engaged end of the arm J being substantially vertical and its movement in an arc, said arm can be raised by the operator out of engagement without any slackening of the train.

It is the intention that the shaft G shall be of such length as that the operator may actuate the same from either end without going between the cars, and thereby jeopardizing 105 his life or limbs. As the shaft G at each end extends beyond the buffer A, there is no risk of injury to the hands of the operator in operating said shaft.

If it is desired to lock the coupling, the 110 platform C may be extended slightly beyond the bar G², and the recess C' may be a slot in said platform in the line of the oscillation of the bar G², and the latter projected sufficiently above the platform C to allow of a padlock or 115 bar being locked in the upper end of said bar G², which will prevent the latter being brought downward through the slot C', and thereby prevent the oscillation of the shaft G.

What I claim as my invention, and desire to 120 secure by Letters Patent of the United States, is—

1. In a coupling, the combination of the buffer A, provided with the recesses D and D' and with a cam, K, the shaft G, seated transversely in said buffer A, provided with a collar, M, having the recess M' therein, and the spring N, substantially as shown, and for the purpose described.

2. In a car-coupling, the combination of the buffer A, provided with recesses D and D', the platform C, having the recess C', the shaft G,

seated transversely in said buffer below said platform and provided with the cross-bar G², adapted to engage said recess C', the spring N, seated on said shaft and adapted to hold the bar G² in engagement with the recess C', and the arm J, seated on said shaft G, substantially as shown, and for the purpose described.

3. In a car-coupling, the combination of the buffer A, provided with the recesses D and D' and the central recess, E, and vertical pin-hole E', an external cam, K, the shaft G, seated transversely in said buffer A and provided with a collar, M, having a recess, M', therein, and with a feather, G', and cross-bar G², the platform C, provided with the recess C', the arm J, seated and adjustable laterally on the shaft G and provided with the recess J', and the

spring N, substantially as shown, and for the purpose described.

4. In a car-coupling, the combination of the buffer A, provided with the recesses D and D' and with the cam K, the platform C, provided with the recess C' therein, the shaft G, seated transversely in said buffer and provided with a collar, M, having a recess, M', therein, and with the cross-bar G², the arm J, provided with a vertical downwardly-extending end, and the spring N, substantially as shown, and for the purpose described.

In testimony whereof I affix my signature in presence of two witnesses.

JACOB HAISH.
